UNITED STATES PATENT OFFICE

140,992

DESIGN FOR A COMBINATION REFRESHMENT COUNTER AND SEAT

Paul A. De Belling, Los Angeles, Calif., assignor of one-half to Frederick A. Bertram, Los Angeles, Calif.

Application December 5, 1944, Serial No. 116,706

Term of patent 3½ years

(Cl. D80—2)

To all whom it may concern:

Be it known that I, Paul A. De Belling, a citizen of the United States, residing at Los Angeles, in the county of Los Angeles and State of California, have invented a new, original, and ornamental Design for a Combination Refreshment Counter and Seat, of which the following is a specification, reference being had to the accompanying drawing, forming part thereof.

Fig. 1 is a front perspective view of a combination refreshment counter and seat embodying my new design.

Fig. 2 is a rear perspective view thereof.

I claim:

The ornamental design for a combination refreshment counter and seat, substantially as shown.
